CHARLES ADIN FOX

BY *Emtharrington*

APPENDIX

UNITED STATES PATENT OFFICE

2,414,732

BIRD GUARD FOR ELECTRICAL PROTECTIVE DEVICES

Charles Adin Fox, Oakland Village, Mo., assignor
to James R. Kearney Corporation, St. Louis,
Mo., a corporation of Missouri

Application February 7, 1945, Serial No. 576,603

7 Claims. (Cl. 174—139)

1

This invention relates generally to electrical protective devices which are adapted for use in protecting equipment associated with electrical circuits in which the protective devices are interposed, from the damaging effects of overloads, short-circuits, and surges, the predominant object of the invention being to provide an electrical protective device of the type mentioned that includes guard means which is so arranged as to prevent a bird from short-circuiting the device by perching on a live part of the device and pecking at another grounded part of the device so as to thereby establish a short-circuit between said parts through the body of the bird.

Fig. 1 is a front elevation of a combination cutout and lightning arrester which is provided with a bird guard in accordance with this invention.

Fig. 2 is a horizontal section taken on line 2—2 of Fig. 1.

Fig. 3 is a fragmentary side elevation of the lower portion of the protective device illustrated in Fig. 1.

In the drawing, wherein is shown for purposes of illustration, merely, one embodiment of the invention, A designates generally an electrical protective device. The particular protective device illustrated in the drawing comprises an insulator 1, of the petticoat type, at the upper end of which an upper terminal 2 is suitably fixed. The upper terminal 2 has secured thereto an outstanding contact arm 3, and said upper terminal 2 includes a loop portion 4 to which the incoming conductor (not shown) of the protective device may be attached by a suitable connector 5.

At its lower end the insulator 1 has suitably secured thereto a lower terminal 6 on which a lower contact arm 7 is mounted, and to which the outgoing conductor (not shown) of the protective device A may be attached by a suitable connector 6. The lower contact arm 7 is formed from a length of wire, or rod material, which is inherently resilient, said lower contact arm being so shaped and arranged as to have a loop portion 8 which is secured to the lower terminal 6 by a bolt and washer assembly 9, a pair of spaced coils 10 into the centers of which are extended contact arm portions which lead from said loop portion 8, portions 11 which lead from the outer portions of the coils and merge into convergent contact arm portions 12, closely related, parallel portions 13 which extend from said convergent portions 12, and rearwardly bent portions 14 at the outer ends of the portions 13 which provide fuse link gripping portions. The outer end portion of the

2

lower contact arm 7 has applied thereto a cap 15, and the closely related, parallel portions 13 of said lower contact arm are embraced by bands 16.

The upper contact arm 3 is provided at its outer end with fuse link gripping portions similar to the fuse link gripping portions provided by the rearwardly bent portions 14 of the lower contact arm 7, and flexible conductors 17 and 18 of a fuse link F are gripped by said fuse link gripping portions of said upper and lower contact arms when the protective device is in a fused condition, as is shown in Fig. 1. The fuse link F includes a fusible section (not shown) which is embraced by a tube 19 formed of suitable insulating material, and when the conductors 17 and 18 of the intact fuse link are engaged by the gripping portions of the upper and lower contact arms 3 and 7, the outer end portion of the lower contact arm 7 is held in an elevated position by the fuse link. Because of the maintenance of the outer end portion of the lower contact arm 7 in an elevated position by the intact fuse link the spirally coiled portions 10 of said lower contact arm are tensioned so that force is stored up in said coiled portions which tends to swing the outer portion of the lower contact arm 7 downwardly, and when the fusible portion of the fuse link is ruptured by a short-circuit or overload in the circuit the outer portion of said lower contact arm swings downwardly to quickly separate the portions of the ruptured fuse link.

The protective device A illustrated in the drawings includes, also, means for arresting surges caused by lightning and other causes. The surge arresting means comprises a member 20 which is suitably supported by the upper terminal 2 and extends outwardly therefrom. Associated with the member 20 is an arm 21 which is so related to said member 20 that a gap 22 is provided between a portion of said member 20 and a portion of said arm, as is shown in Fig. 1. The arm 21 is fixed to a support 23 which is secured to the insulator 1 by a U-bolt 24, said support 23 having secured to it, also, an upper contact arm 25.

The insulator 1 of the protective device A is provided with a bracket 26 which serves as means for mounting the device on a cross arm, or other support. The bracket 26 includes a portion 27 which embraces a portion of the insulator 1, and fixed to a supporting element 28, which is associated with said embracing portion of said bracket, is a lower contact arm 29. The lower contact arm 29 is constructed and arranged in accordance with the lower contact arm 7, previously described herein, said lower contact arm 29 being

formed from a length of resilient wire, or rod material, and being provided with spaced, spirally coiled portions 30, one of which is shown in Fig. 1, and having rearwardly bent portions 31 at its outer end, one of which is shown in Fig. 1, which provide said lower contact arm 29 with gripping portions. The upper contact arm 25 is provided with rearwardly bent portions 32 at its outer end, one of which is shown in Fig. 1, that produce gripping portions, and the gripping portions of said upper contact arm 25 and said lower contact arm 29 engage flexible conductors 33 and 34 of a surge tube structure S which is of suitable construction and arrangement to perform its intended function.

The bracket 26 is grounded, as is indicated diagrammatically in Fig. 1, and when, in the use of the protective device A, a surge on the line seeks a path to ground it will form an arc across the air gap 22 (which normally keeps the line potential off of the surge tube structure S) and across a gap (not shown) within the surge tube structure S, and will pass to ground by way of the lower contact arm 29 and the bracket 26. A follow-up power arc will be established across the gap within the surge tube structure and this follow-up power arc will be extinguished within the surge tube structure. If, however, the surge tube structure fails to properly extinguish the power arc, the continuance of the arc will destroy the surge tube structure by burning same so that its opposite end portions are separated, and when this occurs the outer end portion of the lower contact arm 29 will swing downwardly in response to force imparted by the tensioned spirally coiled portions 30 of said lower contact arm 29 to quickly jerk the surge tube structure S apart, and thereby free the protective device from ground by creating an air gap which will prevent re-establishment of an arc.

It has been found in the use of an electrical protective device such, for instance, as that shown in the drawing hereof and described above, that birds frequently perch on the upper portions of the energized, spirally coiled portions 18 of the lower contact arm 7, and peck at adjacent grounded portions of the surge arresting means of the device. When this occurs a short-circuit is established through the body of the bird from the lower contact arm 7 to ground and the fuse link F is ruptured, thereby interrupting service on the circuit. The prime purpose of this invention is to provide a protective device with means which prevents a bird from so short-circuiting the protective device, and this means will now be described.

The preventive means referred to above comprises a guard in the form of a sheet 35 of electrical insulating material which possesses the required resiliency, one material which has been found to be entirely suitable for the purpose being Bakelite. The sheet 35 of insulating material is of partial circular shape, as is shown in Fig. 2, and said sheet of material is provided with a cutout portion 36 which likewise is of partial circular shape and is eccentrically arranged with respect to the partially circular sheet 35. The wall of the cutout portion 36 and the outer marginal edge of the partially circular sheet of material 35 are joined by a pair of flared edge portions 37 of the sheet of material which provide a tapered opening portion that serves as an entrance to the partially circular cutout portion 36.

The sheet of material 35 is applied to a portion of the insulator 1 which defines the recess be-

tween the lowermost petticoat of the insulator and the next higher petticoat, and when so applied the sheet of material is disposed immediately above the coiled portions 18 of the lower contact arm 7, as is shown in Figs. 1 and 3. To apply the sheet of material to the insulator, said sheet of material is arranged in a horizontal position at the recess of the insulator where it is to be applied, with the recessed insulator portion extending partially into the cutout portion of the sheet of material, as is shown by dotted lines in Fig. 2. The sheet of material is then forced onto the recessed insulator portion so that the partially circular edge of the cutout portion 36 contacts closely with the circumferential face of the recessed insulator portion.

It is important to note that the diameter of the cutout portion 36 of the sheet of material 35 is slightly less than the diameter of the insulator portion at the base of the recess in which the sheet of material is applied to the insulator, and because of this fact, and due to the resilient nature of the sheet of material, portions of said sheet of material will yield as the sheet of material is forced onto the insulator. Also, when the sheet of material has been completely applied to the insulator the edge of the cutout portion 36 of the sheet of material 35, which describes an arc of greater than 180° of a circle, will closely grip a corresponding portion of the circumferential face of the insulator portion to which said sheet of material is applied, and hence the sheet of material 35 will be very securely attached to the insulator 1 of the protective device A without the need for fastening devices of any sort for accomplishing such attachment.

When the guard has been applied to the insulator as described, it overlies the coiled portions 18 of the lower contact arm 7 so that a bird may not perch thereon, as has been possible in the past when no protective guard was employed. Also, if a bird should perch on the guard and peck at a grounded part of the protective device no short-circuit would be produced because of the electrical insulating nature of the guard.

If desired, the sheet of material 35 which provides the guard may be provided with a down-turned lip 38, which, when the guard is in place in association with the insulator 1, is disposed between the spaced coils 16 of the protective device A. The lip 38 is of only slightly less width than the space between the spaced coils 16, and hence the disposition of said lip between said spaced coils will prevent any rotation of the guard with respect to the insulator if there should be any looseness between the edge of the cutout portion 36 of the guard and the circumferential face of the insulator.

I claim:

1. In combination with an electrical protective device comprising an insulator of the petticoat type that supports an energized device part and a grounded device part, a guard comprising a sheet of electrical insulating material which is supported by said insulator so that it overlies said energized part of said protective device, said sheet of electrical insulating material being provided with a cutout portion and an entrance opening which leads from the outer edge of said sheet of insulating material into said cutout portion, said cutout portion of said sheet of insulating material having an edge which describes an arc of more than 180° of a circle that is seated between an adjacent pair of ribs of said insulator and closely grips a face portion of said insulator lo-

cated between and at the bases of said adjacent pair of insulator ribs to effect attachment of said guard to said insulator.

2. In combination with an electrical protective device comprising an insulator that supports an energized device part and a grounded device part, a guard comprising a sheet of electrical insulating material which is supported by said insulator so that it overlies said energized part of said protective device, said sheet of electrical insulating material being provided with a cutout portion and an entrance opening which leads from the outer edge of said sheet of insulating material into said cutout portion, said cutout portion of said sheet of insulating material being arranged eccentrically with respect to said sheet of insulating material and said cutout portion having an edge which describes an arc of more than 180° of a circle that closely grips a face portion of said insulator to effect attachment of said guard to said insulator.

3. In combination with an electrical protective device comprising an insulator that supports an energized device part and a grounded device part, a guard comprising a sheet of resilient electrical insulating material which is supported by said insulator so that it overlies said energized part of said protective device, said sheet of electrical insulating material being provided with a cutout portion which is arranged eccentrically with respect to said sheet of insulating material, and an entrance opening which leads from the outer edge of said sheet of insulating material into said cutout portion, said cutout portion being adapted to receive therein a portion of said insulator and said cutout portion being of slightly less diameter than the diameter of the insulator portion received therein, whereby the resilient nature of said sheet of insulating material will cause the edge of said cutout portion to closely grip a face portion of the insulator portion received within said cutout portion to effect attachment of said guard to said insulator.

4. In combination with an electrical protective device comprising an insulator that supports an energized device part and a grounded device part, a guard comprising a sheet of resilient electrical insulating material which is supported by said insulator so that it overlies said energized part of said protective device, said sheet of electrical insulating material being provided with a cutout portion which is arranged eccentrically with respect to said sheet of insulating material and an entrance opening which leads from the outer edge of said sheet of insulating material into said cutout portion, said cutout portion being adapted to receive therein a portion of said insulator and said cutout portion being of slightly less diameter than the diameter of the insulator portion re-

ceived therein and having an edge which describes an arc of more than 180° of a circle, whereby the resilient nature of said sheet of insulating material and the shape of said cutout portion will cause the edge of said cutout portion to closely grip a face portion of the insulator portion received within said cutout portion to effect attachment of said guard to said insulator.

5. In combination with an electrical protective device comprising an insulator that supports an energized device part and a grounded device part, a guard comprising a sheet of electrical insulating material which is supported by said insulator so that it overlies said energized part of said protective device, said sheet of electrical insulating material being provided with a cutout portion having an edge which closely grips a face portion of said insulator to effect attachment of said guard to said insulator, and an extension on said guard that is disposed adjacent to said energized part and which prevents rotation of said sheet of electrical insulating material with respect to said insulator by abutting against a portion of said energized part.

6. In combination with an electrical protective device comprising an insulator that supports an energized device part and a grounded device part, a guard comprising a sheet of electrical insulating material which is supported by said insulator so that it overlies said energized part of said protective device, said sheet of electrical insulating material being provided with a cutout portion and an entrance opening which leads from the outer edge of said sheet of insulating material into said cutout portion, said cutout portion of said sheet of insulating material having an edge which describes an arc of more than 180° of a circle that closely grips a face portion of said insulator to effect attachment of said guard to said insulator, and an extension on said guard that is disposed adjacent to said energized part and which prevents rotation of said sheet of electrical insulating material with respect to said insulator by abutting against a portion of said energized part.

7. In combination with an electrical protective device comprising an insulator that supports an energized device part and a grounded device part, a guard comprising a sheet of electrical insulating material which is supported by said insulator so that it overlies said energized part of said protective device, said sheet of insulating material being provided with a cutout portion having an edge which closely grips a face portion of said insulator to effect attachment of said guard to said insulator, and an extension on said guard which is adapted to abut against a part of said protective device so as to prevent rotation of said guard with respect to said insulator.

CHARLES ADIN FOX.
